RAILWAY RAIL JOINT

Filed June 11, 1929

Inventor
W. A. Evers

Attorney
Watson E. Coleman

UNITED STATES PATENT OFFICE

WILLIAM A. EVERE, OF MARTINSBURG, WEST VIRGINIA

RAILWAY-RAIL JOINT

Application filed June 11, 1929. Serial No. 370,060.

This invention relates to railway rail joints, and has for one of its objects to provide a novel device of this character which shall be adapted to hold the ends of the rails against any relative vertical or horizontal movements, and which shall effect such a connection between the heads of the rails as to reduce to the minimum the jars incident to the passage of the wheels of a car over the joint and to prevent the wheels from bruising the ends of the heads of the rails.

To attain the foregoing and other objects, the nature of which will appear as the description proceeds, the invention comprehends the overlapping of the ends of the rail heads, the provision of one rail web with a terminal recess adapted to receive a terminal extension on the other rail web, and the provision of joint plates having horizontal upper and lower edges contacting with similar surfaces or seats at the upper sides of the rail bases and at the lower sides of the rail heads.

The invention is hereinafter more fully described and claimed, and illustrated in the accompanying drawings, wherein:

Figure 1 is a view in side elevation of a rail joint constructed in accordance with my invention;

Figure 2 is a top plan view of the rail joint;

Figure 3 is a sectional view taken on the horizontal plane indicated by the line 3—3 of Figure 1;

Figure 4 is a sectional view taken on the vertical plane indicated by the line 4—4 of Figure 1;

Referring in detail to the drawings, 1 designates the bases, 2 the webs, and 3 the heads of a pair of railway rails. In accordance with my invention, the inner and outer base flanges of the rails are provided with horizontal upper surfaces or seats 4, the under sides of the heads 3 are provided with

horizontal surfaces or seats 5, and the ends of the rails are beveled, as at 5^a. The web of one of the rails extends beyond the base and head of the rail, and this extension or tongue 6 fits in a recess 7 formed in the end of the other rail by cutting away a portion

of its web. The tongue 6 contacts with the upper side of the base 1 and the lower side of the head 3, which sides constitute the upper and lower walls of the recess 7, and the vertical wall of the recess and the vertical edge of the tongue 6 are beveled, as at 8 and 9.

Joint plates 10 and 11 are provided with horizontal upper and lower sides which contact with the seats 4 and 5 of the rails. The joint plates 10 and 11 extend in opposite directions beyond the meeting edges of the bases 1 and heads 3 and extend in opposite directions beyond the meeting edges of the webs 2, and are secured in place by bolts 12. 55 The joint plates 10 and 11 snugly contact with the seats 4 and 5, and are of solid formation and they are thicker than the width of the seats 4 and 5. The beveled ends of the bases 1 and heads 3 are straight and of uniform thickness throughout their entire length and are arranged in a common plane. The beveled wall of the recess 7 and the beveled edge of the tongue 6 are also straight throughout their entire length and width and are 60 arranged in a plane parallel to the plane of the beveled edges of the bases 1 and heads 3. In addition to contacting throughout their entire length with the seats 4 and 5, the joint plates 10 and 11 contact throughout 65 their entire length with the webs 2.

It will be understood from the foregoing description, taken in connection with the accompanying drawings, that in all forms of the rail joint the web of one rail is provided with an extension which fits in a recess in the end of the other rail and contacts with the upper and lower walls of the recess, that the plates extend in opposite directions beyond the meeting ends of the rail bases and heads and the meeting ends of the webs, and that the joint plates and the rail bases and heads are provided with flat and horizontal abutting surfaces.

It will be further understood that rail joints embodying these features are strong and durable, hold the rails against any relative vertical or horizontal movements, and insure, no matter to what extent the rails may contract in cold weather, passage of 95 100

the wheels thereover with the minimum of noise and injury to the ends of the rail heads.

While I have described the principle of the invention together with the structure which I now consider the preferred embodiment therof, it is to be understood that the structure shown is merely illustrative and that such changes may be made, when desired, as fall within the scope of the invention as claimed.

10 I claim:—

1. In combination, rails having the ends of their bases and heads beveled, the beveled ends of the bases and heads being straight throughout their entire length and arranged in a common plane and the ends of the heads being of uniform thickness throughout their entire width, the web of one rail being cut away to provide a recess extending from the base to the head of the rail, an extension on the end of the web of the other rail and fitting in said recess and contacting with the upper and lower walls thereof, the vertical wall of the recess and the corresponding edge of the web extension being beveled and straight throughout their entire length and arranged in a plane parallel to that of the beveled ends of the bases and heads, and thick joint plates secured to the webs and extending beyond the adjacent ends of the bases, heads and webs and contacting throughout their entire length with the bases, heads and webs.

2. In combination, rails having the ends of their bases and heads beveled, the beveled ends of the bases and heads being straight throughout their entire length and arranged in a common plane and the ends of the heads being of uniform thickness throughout their entire width, the web of one rail being cut away to provide a recess extending from the base to the head of the rail, an extension on the end of the web of the other rail and fitting in said recess and contacting with the upper and lower walls thereof, the vertical wall of the recess and the corresponding edge of the web extension being beveled and straight throughout their entire length and arranged in a plane parallel to that of the beveled ends of the bases and heads, the rails being provided at the upper sides of their base flanges and at the lower sides of their heads with straight horizontal seats, and thick joint plates secured to the webs and extending beyond the adjacent ends of the bases, webs and heads and contacting throughout their entire length with the webs, the joint plates being provided with flat horizontal upper and lower sides contacting throughout their entire length with said seats.

In testimony whereof I hereunto affix my signature.

WILLIAM A. EVERE
